The ornamental design for a front surface of a returning wall module, as shown and described.

DESCRIPTION

U.S. PATENT DOCUMENTS

FIG. 1 is a perspective view of a first embodiment of the front face of a retaining wall module shown in condition for use with other retaining wall blocks;
FIG. 2 is a greatly enlarged view of the front face of the retaining wall module shown in FIG. 1, shown separately for clarity of illustration;

- D. 22,609 * 7/1893 Deslauriers D25/151
D. 22,610 * 7/1893 Deslauriers D25/151
D. 67,647 * 6/1925 Dunn D25/118
D. 134,608 * 12/1942 Larson D25/114

FIG. 3 is a perspective view of a second embodiment of the front face of a retaining wall module shown in condition of use with other retaining wall blocks; and,

FIG. 4 is a greatly enlarged view of the front face of the retaining wall module shown in FIG. 3, shown separately for clarity of illustration.

The broken line showing of a sectional retaining wall is for illustrative purposes only and forms no part of the claimed design.
